Patented Apr. 7, 1964

197,889

COMBINED GUM AND MUSCLE EXERCISER OR THE LIKE

Martin A. Hass, 1055 Medio Drive,
Pacific Palisades, Calif.

Filed Feb. 18, 1963, Ser. No. 73,605

Term of patent 14 years

(Cl. D24—1)

FIGURE 1 is a front perspective view of a combined gum and muscle exerciser or the like showing my new design;

FIGURE 2 is a top plan view thereof;

FIGURE 3 is a side elevation thereof; and

FIGURE 4 is a bottom plan view thereof.

I claim:

The ornamental design for a combined gum and muscle exerciser or the like, substantially as shown.
